CLAIM

The ornamental design for a thermometer as shown and described.

DESCRIPTION

- 1.1: Front View
- 1.2: Back View
- 1.3: Left View
- 1.4: Right View
- 1.5: Top View
- 1.6: Bottom View
- 1.7: Front Perspective View
- 1.8: Back Perspective View
- 1.9: Front View, Alternate Configuration
- 1.10: Front View, Another Alternate Configuration
- 1.11: Enlarged View
- 1.12: Enlarged View
- 1.13: Enlarged View
- 1.14: Enlarged View

The dash-dash broken lines in the drawings illustrate the portions of the thermometer that form no part of the claimed design.

The dot-dash broken lines in the drawings depict the boundaries of the partial enlarged views that form no part of the claimed design.

1 Claim, 14 Drawing Sheets
